(57) **CLAIM**

The ornamental design for an adjustable work table, as shown and described.

DESCRIPTION

FIG. 1 is a top, front, left side perspective view of an adjustable work table, showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front, left side perspective view showing the adjustable work table in extended state;

FIG. 10 is an enlarged view of the portion 10 in FIG. 1; and,

FIG. 11 is an enlarged view of the portion 11 in FIG. 2.

The evenly dotted broken lines illustrate portions of the adjustable work table and form no part of the claimed design. The unevenly dashed broken lines define the boundaries of enlarged views and form no part of the claimed design.

1 Claim, 11 Drawing Sheets
